UNITED STATES PATENT OFFICE.

JOHN ROURKE, OF NORWICH, CONNECTICUT.

ROTARY MOP.

SPECIFICATION forming part of Letters Patent No. 397,521, dated February 12, 1889.

Application filed December 12, 1887. Serial No. 257,718. (No model.)

To all whom it may concern:

Be it known that I, JOHN ROURKE, a citizen of the United States, residing at Norwich, in the county of New London and State of Connecticut, have invented certain new and useful Improvements in Rotary Mops, which improvements are fully set forth and described in the following specification, reference being had to the accompanying three sheets of drawings, in which—

Figure 1 is a perspective of my said device, and Fig. 2 a longitudinal section of the same slightly enlarged. Fig. 3 is an inner side view of one of the end frames with the traction-wheel d and its gear attached to said frame. Fig. 4 is a view taken through the clear-water chamber looking toward partition h^2 . Fig. 5 is a detached perspective view of the water-pan A. Fig. 6 is a detached perspective view of the revolving barrel which carries the series of mops. Fig. 7 is a detached view of the gutter used to conduct dirty water into the receptacle provided for the same. Fig. 8 is a cross-section of the dirty-water pan looking toward the partition that separates said pan from the clean-water chamber. Fig. 9 is an enlarged perspective view of the valve which controls the outflow of clean water. Fig. 10 is a cross-section of the water-pan A on line z, Fig. 2, looking toward partition h^2 .

My invention consists of a mechanical device for sprinkling and mopping floors, tiling, and like surfaces, and has for its object the production of a portable machine of moderate cost which may be used on bare floors to perform the work of both a broom and mop. Said device also sprinkles the floor in advance of the mops and wrings out the dirty water as said mops rotate, the construction and operation of said machine being described in detail hereinafter.

The general principle of my device is that of a rotary drum carrying a series of mop-cloths, said drum being kept in motion by a train of gearing operated by traction-wheels in substantially the manner common to rotary lawn-mowers. Within this drum is another drum or cylindrical vessel concentric with the first, but non-rotatable. This latter drum I term my "water-pan." Adjacent to the revolving (outer) drum is a roller, under which the mops

pass and are squeezed to remove a portion of the dirty water. The fixed water-pan is preferably provided with two compartments, one of which receives the dirty water from the wringer, while the other delivers jets of clean water in front of the mops, as I have described more fully hereinafter.

Referring to the annexed drawings, the letters a a' indicate the main frames of my device, having angle-arms a^2 , which approach each other in the rear of the mopping mechanism and support an operating-handle, a^3 .

b b' indicate cylinder-heads, having formed on their outer faces gears c c' , and connected by sheet-metal strips b^2 , located in a practical machine about two inches apart. Projecting outward from gears c c' are hollow bearings c^2 , adapted to enter recesses c^3 in the main frames a a' and to rotate freely therein. Journaled to the inner lower side of said main frames are traction-wheels d d' , formed with gears d^2 , which engage and transmit motion to the cylinder-heads b b' , above described.

Extending from one of said cylinder-heads to its companion are wires e , on which are hung mop-cloths e' , formed, preferably, of sections of stockinet or similar soft textile goods. When in use, these mop-cloths are rapidly carried around with the cylinder just described, and wipe the floor as they are carried underneath said cylinder. Immediately over said revolving cylinder is a roll, f , journaled in the frames a a' and covered with a jacket of rubber, f' . This roller is adjustable vertically, being controlled by adjusting-screws g . As the mop-cloths pass beneath said roller, they are squeezed between said roller and the sheet-metal strips b^2 to remove a portion of the dirty water contained therein.

Within the revolving cylinder above described and concentric therewith is another smaller cylinder or circular pan, A, which is suspended fixedly by a shaft, h , which extends outward through the hollow bearings c^2 and through the main frames a a' , being held in place by nuts h' , screwed tightly onto the ends of said shaft. (See Fig. 2.) Cylinder A is secured to said shaft h , preferably by soldering. A partition, h^2 , divides said fixed cylinder A into two compartments, one of which (the right-hand one, as here shown) is pro-

- vided to receive the dirty water wrung from the mop-cloths by roller f , and the companion chamber is used as a reservoir for clean water with which to sprinkle the floor and mops.
- 5 The lower portion of cylinder A is partitioned off to form a separate chamber, i , which extends from end to end of said cylinder, and has a series of openings, i' , leading outward and downward therefrom. The chamber or 10 sprinkler thus provided is connected with the clean-water reservoir by a peculiar valve, which is illustrated in Figs. 8 and 9.
- k indicates a metal plate attached by rivet to the partition h^2 and having secured there- 15 to an operating-handle, k' , which extends upward within reach of the operator and by which the valve-plate k may be swung on its pivot. On the inner side of said plate is a 20 packing, k^3 , of soft material—as rubber or leather—which moves with said plate k , and is provided with a slot, k^4 . In the partition h^2 are two holes, m n , the former of which leads from the clean-water reservoir into the dirty-water chamber, and the latter, n , leads 25 from said dirty-water chamber into the sprinkling-chamber i . The valve k is so pivoted that its rubber packing may cover both holes m n , or may be swung on its pivot to bring the slot k^4 over said holes, in which latter 30 case a continuous opening is provided between the clean-water reservoir and the sprinkling-chamber i —that is to say, the water passes through hole m into and along slot k^4 until it finds an exit through hole n into 35 said sprinkling-chamber. When it is not desired to use said sprinkling-chamber, the raising of the operating-handle k' acts to move and close the valve and thus shut off the out- 40 flow of clean water.
- 40 To prevent the dirty water from flowing into the clean-water chamber as it is wrung from the mops, I provide a removable gutter or conductor, o , formed with sufficient pitch to lead the water toward the dirty-water chamber. This conductor o slips under a sheet-metal bar, p , extending across and over said 45 clean-water chamber, and, when in position, forms both a cover for said clean-water chamber and a conductor for the purpose named.
- 50 I have found in practice a tendency on the part of the wet mop-cloths to adhere to the sections b^2 of the revolving cylinder instead of dropping freely to the floor as they pass around from the wringer, and to overcome this 55 difficulty I provide wires v , extending from one cylinder-head, b , to its companion head, so located that the free portion of the mop-cloths may rest thereon as they pass upward to the wringer. These wires, after the cloths 60 pass said wringer, act to raise slightly the damp cloths from contact with the sheet-metal sections b^2 , and by thus admitting air

under said cloths overcome the said tendency to adhere.

Assuming that the clean-water reservoir is 65 filled and ready for use, the action of my device is as follows: The operator presses down the valve-rod k' and starts the flow of clean water through the openings i' . Now, as he pushes the machine forward along the floor, 70 the traction-wheels d d' and their attached gears cause the outer cylinder to rotate and carry around with it the mop-cloths e' , which drag along the floor during a part of each revolution and wipe up the dirt and dust in 75 their path. Meanwhile the clean water trickles down upon said revolving mops and upon the floor. As the mops gather up the water and dirt they pass upward under roll f' , when a considerable part of the water is squeezed 80 out and runs down into the dirty-water chamber; from which it may be poured by inverting the machine.

I claim as my invention and wish to secure by Letters Patent—

85 1. In combination with the supporting-frames a a' , traction-wheels journaled thereto, a cylinder rotatably journaled in said frames and connected with said traction-wheels by gears, as set forth, a series of mop-cloths carried by said cylinder, a wringer-roll journaled in said frames in the path of said mop-cloths, and a water-receptacle within said cylinder, said receptacle being fixedly supported by a shaft extending outward through frames a a' 90 and secured by nuts at each end, all substantially as and for the purpose specified.

95 2. In combination with frames a a' , traction-wheels journaled thereto, a cylinder rotatably journaled in said frames and connected with said traction-wheels by gears, as set forth, a series of mop-cloths carried by said cylinder, a wringer-roll journaled in said frames in the path of said mop-cloths, a fixed 100 water-receptacle supported within said rotatable cylinder by a shaft extending outward through frames a a' , said fixed receptacle being divided by lateral and longitudinal partitions into three compartments, the lowest of which is perforated to discharge the water, 105 as set forth, said discharge-compartment being connected with one of the adjacent compartments by a valve formed of a pivoted plate having a slot, as at h^4 , that may be brought into coincidence with openings leading from one of the upper or storage compartments to said lower or discharge compartment, all being substantially as and for the purpose 110 specified.

JOHN ROURKE.
